DESIGN FOR A CARPET.

SPECIFICATION forming part of Design No. 12,211, dated March 29, 1881.

Application filed February 10, 1881. Term of patent 33 years.

To all whom it may concern:

Be it known that I, WINTHROP L. JACOBS, of Jersey City, in the county of Hudson and State of New Jersey, have invented a new and 5 original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figures A indicate a vine-like figure running irregularly over the design, with various projections, stems, and branches thereon. The figure A bears upon it numerous figures of varied shapes. B is a circular rosette-like figure. C is a circular figure. D is a circular 15 figure. E is a bud-like figure. G is shaped like a palm-leaf. H is circular and indented. I resembles a flower, and is placed on the vine A, between G and the figure J, which resembles a bud. K is a leaf-like figure. 20 L also resembles a flower. M and N are circular. O is bud-shaped. P resembles a cluster of leaves, and Q is a conical flower, from whose stem projects the figure R. S somewhat resembles a palm-leaf, and V is a circular flower with pointed petals. 25
